Wm S. Corwin

Oscar A. Michel.

—INVENTOR:—

William Roemer,

BY *Draude & Co. ATT'YS.*

UNITED STATES PATENT OFFICE.

WILLIAM ROEMER, OF NEWARK, NEW JERSEY.

FIXTURE FOR BAG-FRAMES.

SPECIFICATION forming part of Letters Patent No. 358,987, dated March 8, 1887.

Application filed September 18, 1886. Serial No. 213,851. (No model.)

To all whom it may concern:

Be it known that I, WILLIAM ROEMER, a citizen of the United States, residing at Newark, in the county of Essex and State of New Jersey, have invented certain new and useful Improvements in Fixtures for Bag-Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to certain improvements in fixtures for bag-frames of the class illustrated in my prior patent, No. 350,641, the object being to provide more durable and effective fixtures at a reduced cost of manufacture.

20 This invention consists in an improved fastener for bag-frames having a bar, frame, or box with a tang to engage a co operating fastener at the side, and recesses for the handle or shoulder-strap of the bag at the ends thereof, and said co-operating fastener, said parts being in combination, and in the arrangements and combinations of parts, substantially as will be hereinafter set forth, and finally embodied in the clauses of the claim.

25 Referring to the accompanying drawings, in which like letters represent corresponding parts in each of the several figures thereof, Figure 1 is a plan view, and Fig. 2 a side elevation, of a combined handle-holding attachment and bag-fastener embodying my improvement. Fig. 3 is a side elevation of the part of the fastener attached to the lower or underlapping "jaw" of the bag-frame. Figs. 4 and 5 are plans, parts being broken away, of peculiar constructions of my improved fastener; and Fig. 6 shows the improved fastener mounted on the top and sides of a bag-frame.

30 In said drawings, *a* is a box, bar, or frame of metal, having a tongue-shaped protuberance or tang, *c*, at the side, and having rivet-holes *i i* and eyes or slots *d d* at the ends thereof, the said eyes or slots being adapted to receive and hold rings attached to the ends 35 of the handle or the ordinary shoulder-strap of the bag.

b is a plate of cast metal, having a slot, *f*, corresponding to the tongue shaped protuberance or tang *c*, and suitable lugs, *g*, (shown in Fig. 3 and indicated in dotted line in Fig. 1,) 55 the said lugs being adapted to be riveted to the lower or underlapping jaw, thus holding said plate *b* firmly and securely to one side of the bag-frame.

The tang *c*, Fig. 1, has a hole, *h*, adapted to 60 receive a suitable pin or padlock, thus fastening the two jaws when in a closed position; or a revolving tang or finger-button may and is preferably provided, as shown in Fig. 4 at *c*², having a pin or rivet-like portion integral 65 therewith, which passes through the side of the box *a*, and is on the under side upset or riveted, as at *k*. By giving the tang *c*² a half-turn the plate *b* may be held in place and the jaws held together in fastened relation, as will 70 be understood.

Still another form of tang is shown in Fig. 5 at *c*³, said tang being hollow and having lugs *l* at the sides thereof, riveted at *m*, and being free to move in the plane of the tang until 75 they engage with suitable stops, as *o*, and held automatically in a separated position by the spring *n*, so that after the tang is passed through the corresponding slot in the plate *b* the said lugs *l* separate automatically and hold 80 the parts together, as will be manifest.

Any other forms of holding device may be employed without departing from the scope of this invention.

The combined fastener and handle-holder 85 may be secured to the top strap or plate of the jaws and a modification of the fastener to the side straps or plates thereof, as shown in Fig. 6 at *b* *c*² and *b'* *c'*, respectively, thus holding the frame, when closed, firmly and securely.

Having thus fully described my invention, what I claim as new is—

1. A fastener for bag-frames, combining 95 therein a bar, frame, or box having a tang at the side and recesses for the handle or shoulder-strap at the ends thereof, and a plate, *b*, with a slot adapted to receive the said tang, substantially as and for the purposes herein set forth.

2. In combination with the jaws or sections of a bag or valise frame, a metal box or bar,

a, with a revolving tang or thumb-button, *c*², riveted or otherwise secured at *k*, and a co-operating fastener, substantially as herein shown and described.

5 3. In combination with the jaws or sections of a bag or valise frame, a cast-metal box provided with a tang at or about in the center of one of the sides thereof, and a cast-metal plate provided with a slot corresponding to said 10 tang, and suitable lugs for securing said plate,

substantially as and for the purposes herein described.

In testimony that I claim the foregoing I have hereunto set my hand this 15th day of September, 1886.

WM. ROEMER.

Witnesses:

CHARLES H. PELL,
WM. S. CORWIN.
